UNITED STATES PATENT OFFICE.

PERMELIA JULIAN, OF RED BRIDGE, INDIANA.

DESIGN FOR A PIE-HOLDER.

SPECIFICATION forming part of Design No. 22,921, dated November 28, 1893.

Application filed October 20, 1893. Serial No. 488,737. Term of patent 7 years.

To all whom it may concern:

Be it known that I, PERMELIA JULIAN, a citizen of the United States, residing at Red Bridge, in the county of Wabash and State 5 of Indiana, have invented a new and original Design for Pie-Holders, of which the following is a specification.

The invention relates to a new and original design for pie-holders.

10 The object of the present invention is to provide an ornamental and attractive pie-holder; and the essential feature resides in a cylindrical frame having a vertical series of horizontally disposed rings or bands, a series 15 of circular plates, and a vertical series of ornamental rings arranged at intervals at the exterior of the frame.

The figure of the drawing is a perspective view of a pie-holder showing my new and 20 original design.

Referring to the drawing, 1 designates a cylindrical frame having a vertical series of horizontally disposed rings 2 and provided

with vertical bars or supports 3, and constructed of ornamentally twisted wire. 25

4 designates a vertical series of horizontally disposed circular plates located adjacent to the horizontal rings 2.

At the sides of the frame adjacent to the ornamental supports 3 are arranged vertical 30 series of connected vertical rings 5. At the bottom of the frame are arranged ornamental feet 6.

It will be readily seen that the design presents an ornamental and attractive appearance. 35

What I claim is—

The design for a pie-holder herein shown and described.

In testimony that I claim the foregoing as 40 my own I have hereto affixed my signature in the presence of two witnesses.

PERMELIA JULIAN.
